CLAIM

The ornamental design for an earphone protective cover, as shown and described.

DESCRIPTION

FIG. 1 is a front, top, and left perspective view of a left earphone protective cover, showing my new design;

FIG. 2 is a front view of the left earphone protective cover;

FIG. 3 is a back view of the left earphone protective cover;

FIG. 4 is a left side view of the left earphone protective cover;

FIG. 5 is a right view of the left earphone protective cover;

FIG. 6 is a top view of the left earphone protective cover;

FIG. 7 is a bottom view of the left earphone protective cover;

FIG. 8 is a back, top, and left perspective view of the left earphone protective cover;

FIG. 9 is a front, top, and left perspective view of a right earphone protective cover, showing my new design;

FIG. 10 is a front view of the right earphone protective cover;

FIG. 11 is a back view of the right earphone protective cover;

FIG. 12 is a left side view of the right earphone protective cover;

FIG. 13 is a right view of the right earphone protective cover;

FIG. 14 is a top view of the right earphone protective cover;

FIG. 15 is a bottom view of the right earphone protective cover; and,

FIG. 16 is a front, top, and left perspective view of the right earphone protective cover.
